COMBINED SCISSORS, SCABBARD, AND LETTER OPENER

John J. Schwartz, St. Paul, Minn., assignor to Brown & Bigelow, St. Paul, Minn.

Application December 2, 1955, Serial No. 39,140

Term of patent 14 years

(Cl. D74—1)

FIG. 1

FIG. 2

FIG. 3

FIG. 4

Figure 1 is a top perspective view of a combined scissors, scabbard, and letter opener showing my new design; Figure 2 is a side elevational view thereof;

The dotted line illustration of scissors as shown in Figures 3 and 4 is for illustrative purposes only.

I claim:

The ornamental design for a combined scissors, scabbard, and letter opener, as shown and described.
